MATERIAL WORKING APPARATUS

Albert E. Jarvis, Arlington, and William J. Keller, Jersey City, N. J., assignors to Western Electric Company, Incorporated, New York, N. Y., a corporation of New York

Application January 8, 1944, Serial No. 517,584

10 Claims. (Cl. 90—11)

This invention relates to material working apparatus, and more particularly to apparatus for slotting tubes.

An object of the invention is to provide a material working apparatus, more particularly one which is simple in structure and highly efficient in cross-slotting tubular articles.

Other objects and advantages will be apparent from the following detailed description when considered in conjunction with the accompanying drawings, wherein:

Fig. 1 is a side elevational view partially in section of an article holding and feeding unit;

Fig. 2 is a fragmentary side elevational view of the apparatus, a portion thereof being shown in section;

Fig. 3 is a fragmentary sectional view taken substantially along the line 3—3 of Fig. 2;

Fig. 4 is a fragmentary sectional view taken substantially along the line 4—4 of Fig. 2;

Fig. 5 is a fragmentary end elevational view taken substantially along the line 5—5 of Fig. 2;

Fig. 6 is an enlarged fragmentary detailed view of a portion of the structure shown in Fig. 4; and

Fig. 7 is a fragmentary end elevational view of the unit shown in Fig. 1, this view being taken substantially along the line 7—7 of Fig. 1.

Referring now to the drawings, attention is first directed to the article holding and feeding unit indicated generally at 10 in Fig. 1. This unit includes a hollow handle portion 11 apertured, at 12, to receive an end 14 of a lever 15. The lever 15 is pivotally supported at 16 and has a handle portion 17 which may be actuated by the operator upon gripping both the handle portions 11 and 17. An actuating pin 18, movably disposed in an aperture 19 of a threaded end 20 of the handle 11, is actuated by the end 14 of the lever 15 to move a chuck 21 into open position. The chuck 21 has a housing 22 mounted upon the threaded end 20 of the handle 11, with a conical aperture 23 in the forward end thereof adapted to receive the chuck 21. The chuck 21 is of the contour shown, having a tubular portion 25, notched longitudinally as at 26, providing resilient portions which normally urge jaws 27 thereof outwardly when the chuck is moved into open position. A member 30, threadedly mounted upon the inner end of the chuck 21, is slidably disposed in the housing 22 and is apertured, at 31, to receive the actuating pin 18. A compression spring 32, disposed in the housing 22 concentric with the adjacent chuck portion, engages the member 30 to normally urge the chuck 21 into closed position, and, through the tapered or con-

ical surfaces thereof indicated at 33, engaging the conical aperture or opening 23 to cause closing of the chuck to grip an article 35. The article in the present instance is tubular in general contour, it being formed of any suitable material such as brass. It will, therefore, be apparent that by actuating the lever 15, the end portion 14 thereof will push the rod or pin 18 toward the chuck end of the unit, first moving the chuck 21 relative to its housing 22 against the force of the spring 32, to cause opening of the chuck, and while in this position an article previously held thereby may be released therefrom and another like article 35 may be disposed in the chuck. Shoulders 36 in the mouth or gripping jaws of the chuck locate the article at a definite position with respect to the chuck when closed. Closing of the chuck is brought about through the force of the spring 32 when the handle portion 17 of the lever 15 is released.

The cutting means includes cutting elements or saws 38 and 39 mounted upon a rotatable shaft 40 for continuous rotation during the use of the apparatus. A holder or body 41 is disposed adjacent the cutting elements 38 and 39 and supports a housing 42 for the latter. Apertures 44 and 45 are formed in the holder 41 of contours similar to the housing 22 and its associated chuck 21, to receive the unit 10 when the article 35 is to be fed to the cutting elements. Associated with the apertures 44 and 45 are grooves 46 and 47 respectively, these grooves extending in transverse directions as illustrated in Fig. 5. The grooves 46 and 47 are for receiving the lever 15, the latter being substantially square in cross-section as illustrated in Fig. 5. Through the aid of the groove 46, the unit 10 is located in a given position to locate this article 35 relative to the cutting element 38. The groove 47 is so positioned as to control the unit 10 through the aid of the lever 15, to cause the cut performed on the article 35 by the element 39 to be at right angles with respect to that performed by the cutting element 38 on the article. When the article 35 is cut by the element 38, the portions of the article on each side of the element 38 are self-supporting against collapsing. However, upon positioning of the unit 10 with the article 35 in the aperture 45, the article has previously been slotted and requires additional support for the side portions thereof upon each side of the element 39. At this position supporting plates or members 49 are disposed in positions to be received in the notches or slots previously cut into the article by the element 38. The plates 49 are

held in desired positions in aligned slots 50 of the holder 41 through the aid of screws 51. The plates serve another purpose in eliminating the possibility of the element 39 slotting the article until the article has first been slotted by the element 38. This is due to the fact that an article 35 without the slot provided by the element 38 cannot be moved into engagement with the element 39.

Referring now to Figs. 2 and 3, it will be noted that the inner ends of the apertures 44 and 45 are tapered, as at 53, to receive the end of the chuck 21, straight portions 54 of the apertures providing abutting surfaces to locate the unit 10 in these apertures. Communicating with the apertures 44 and 45 are article receiving apertures 55 leading toward their respective cutting elements 38 and 39. Also, slots 56 are provided in the holder 41 for the cutting elements 38 and 39. Downwardly projecting passageways 58 (Figs. 2, 4 and 5) eliminate the possibility of particles interfering with the accurate location of the unit 10 in each of the apertures 44 and 45, these passageways communicating with the apertures adjacent the inner ends thereof and extending downwardly and outwardly through the holder 41.

During the operation of the apparatus, the unit 10 is provided with an article 35 in its chuck 21 located therein by the shoulders 36, the chuck having been actuated into open position through the aid of the lever 15. By releasing the lever 15, the chuck is closed through the force of the spring 32 and at this time the article 35, through the aid of the unit 10, may be moved through the apertures 44 and 45. As the unit is moved into the aperture, the article 35, upon reaching the cutting element 38, is slotted to a given depth limited by the abutting surface 54 which the unit 10, particularly the chuck 21 thereof, engages. This inward movement of the unit 10 is controlled through the groove 46 and the lever 15, causing the article to be slotted in a given direction. The unit 10 with the slotted article is removed from the aperture 44, and without varying the location of the article in the unit they are disposed in the aperture 45, their positions therein being controlled by the notch or groove 47. Here again the article 35 is slotted, the slots at this time extending at right angles with respect to the previous slots formed by the cutting element 38. During this last slotting operation the portions of the article are held against collapsing by the plates 49. At the completion of the slotting operation, the unit 10 with the slotted article 35 may be removed from the aperture 45, after which the slotted article may be moved from the unit during actuation of the lever 15, at which time a new article may be disposed in the unit and the slotting operation repeated.

Although specific improvements of the invention have been shown and described, it will be understood that they are but illustrative and that various modifications may be made therein without departing from the scope and spirit of this invention as defined by the appended claims.

What is claimed is:

1. An apparatus for slotting articles comprising rotatable slotting means, a unit for holding an article and feeding it to the slotting means, a support having a plurality of receiving portions for successively guiding the unit in different positions toward the cutting means to cause cutting of slots at different angles in the article by the slotting means, and means receivable in one slot

of the article to support adjacent portions of the article against collapsing during subsequent slotting of the article.

2. An apparatus for slotting articles comprising rotatable slotting elements, a unit for holding an article and feeding it to the slotting means, a support having unit receiving portions disposed adjacent each slotting element for guiding the unit successively toward their slotting elements to cause cutting of slots in the article, and means receivable in a slot in the article cut by one of the slotting elements to hold the article against collapsing during cutting of another slot in the article by another of the elements.

3. An apparatus for slotting articles comprising rotatable slotting elements, a unit for holding an article and feeding it to the slotting means, a support having unit receiving portions disposed adjacent each slotting element for guiding the unit successively toward their slotting elements to cause cutting of slots in the article, and means receivable in a slot in the article cut by one of the slotting elements to hold the article against collapsing during cutting of another slot in the article by another of the elements and adapted to bar slotting of the article by the second element until it has been slotted by the first element.

4. An apparatus for slotting articles comprising spaced rotatable slotting elements, a unit having a chuck actuatable to removably hold an article, a lever and means under the control of the lever to actuate the chuck, and a support having spaced guideways for the unit in alignment with their respective elements to singly guide the unit and cooperating with the lever thereof to cause successive feeding of the article in different positions to the slotting elements to cause cross slotting of the article.

5. An apparatus for slotting articles comprising spaced rotatable slotting elements, a unit having a chuck adapted to removably hold an article, a support having spaced guideways for the unit in alignment with their respective slotting elements to singly guide the unit in different positions to the slotting elements to cause cross slotting of the article, and guideways for the article adjacent the elements and in axial alignment with the guideways for the unit.

6. An apparatus for slotting articles comprising spaced rotatable slotting elements, a unit having a chuck actuatable to removably hold an article, a lever and means under the control of the lever to actuate the chuck, and a support having spaced guideways for the unit in alignment with their respective elements and transverse lever receiving portions cooperating to cause successive feeding of the article in different positions to the slotting elements to cause cross slotting of the article.

7. An apparatus for slotting articles comprising a first and second slotting element mounted at spaced positions on a common axis, a unit having a chuck adapted to removably hold an article, a support having spaced guideways in alignment with their respective slotting elements to singly receive and guide the unit and article toward the elements to cause cross-slotting of the article, and means disposed adjacent the guideway for the second element and receivable in a slot cut in the article by the first element to hold the article against collapsing during slotting of the article by the second element.

8. An apparatus for slotting articles comprising slotting elements mounted at spaced posi-

tions on a common axis, a unit having a chuck adapted to removably hold an article, a support having spaced guideways in alignment with their respective slotting elements to singly receive and guide the unit and article toward the elements to cause cross-slotting of the article, and means to bar movement of the article to the second element until it is slotted by the first element and receivable in the slot cut in the article by the first element to support the article against collapsing during slotting of the article by the second element.

9. An apparatus for slotting articles comprising slotting elements mounted at spaced positions on a common axis, a unit having a chuck adapted to removably hold an article, a support having spaced guideways in alignment with their respective slotting elements to singly receive and guide the unit and article toward the elements to cause cross-slotting of the article, means to bar movement of the article to the second element until it is slotted by the first element and

receivable in the slot cut in the article by the first element to support the article against collapsing during slotting of the article by the second element, and means to locate the unit in the guideway adjacent the second element with the said slot formed by the first element in registration with the last mentioned means.

10. An apparatus for slotting articles comprising slotting elements mounted at spaced positions on a common axis, a unit having a chuck adapted to removably hold an article, a support having sets of apertures therein, one set to receive the unit singly for movement limited distances toward their respective elements, the other set positioned to singly receive the article and direct it to the elements, and means disposed in one of the apertures of the last mentioned set to bar the article from movement to the adjacent element until the article is first slotted by the other element.
